UNITED STATES PATENT OFFICE.

SAMUEL F. NEWMAN, OF WAYNESBORO, PENNSYLVANIA, ASSIGNOR TO LANDIS MANUFACTURE COMPANY, OF WAYNESBORO, PENNSYLVANIA, A CORPORATION OF PENNSYLVANIA.

TRIP FOR DIE HEADS.

Application filed November 17, 1924. Serial No. 750,477.

My said invention relates to trips for die heads and it is an object of the invention to provide means in connection particularly with die heads adapted to form threads on pipe, bolts and the like for interrupting the threading operation after a thread has been cut on a predetermined length of the work.

A further object of the invention is to provide adjustable means in connection with the head whereby the length of the threaded portion may be varied.

Referring to the accompanying drawings, which are made a part hereof and on which similar reference characters indicate similar parts,

Figure 1 is a front elevation of my device in closed position,

Figure 2, a similar view of the device in open position,

Figure 3, a section on line 3—3 of Figure 1,

Figure 4, a section on line 4—4 of Figure 2, and

Figure 5, a section on line 5—5 of Figure 1.

In the drawings reference character 10 indicates a head body which is hollow as usual to permit lengthwise movement of the work part of the way through the body and the bore of which is enlarged at its rear end to accommodate a flange 11 on the shank 12, which flange closes the bore at the rear end to keep out dirt from the rear portion of the bore and also to keep out dirt from the spaces between the body and a radial flange 13 on said shank, the latter flange terminating in a forwardly extending flange 14.

The forwardly extending flange 14 forms one element of a ring frame surrounding the head body, said ring frame comprising in addition to the flange 14 a series of rings 15, 16 and 17 (Fig. 3) of which the ring 16 is held rigidly against rotation relatively to the shank flange 14 by pins 23, hereinafter described. The head body is held rigidly, but adjustably, against such relative rotation by means of a screw (not shown) journaled in bearings in the rings 16 and engaging worm teeth at 18 on the body. The ring 17 is rotatably mounted on the body and is adapted to be oscillated in one direction to open position by resilient means not shown.

The ring 15 is clamped to the head body by a relatively thin ring 20 fitting about a reduced portion of the body and securely held in place by means of screws 21 having threaded engagement with the body, the heads of said screws bearing at one side against a ledge on said ring and at the other side against countersunk portions of the body. The ring 20 serves not only to clamp the ring 15 to the body but also holds the rings 16 and 17 in place, a flange 22 at the front of the body cooperating with the ring for this purpose.

One or more pins 23 are secured to the flange 13, these pins passing through holes in the ring 16 and holding the ring against rotation relatively to the flange 13, thereby also holding the head body and the ring 15 in adjusted position relative to said flange and shank. At their forward ends the pins have reduced portions engaging in recesses in the ring 17 such recesses being preferably provided with hardened bushings indicated at 24 and 25 respectively.

The front face of the head is provided with chaser holders 26 pivoted to the head body at 27 and connected to the ring 17 at 28 by sliding pin and slot connections. Each of the chaser holders has a clamping device 29 extending over a lip 30 on a tangential chaser 31. The clamping device 35 is held in place by screws 32 having threaded engagement with the body of the chaser holder.

The head body has parallel longitudinal bores adapted to receive trunnions 33 which in turn have threaded longitudinal bores 34 for the screws 34' it being understood that the trunnions may be integral with the chaser holders or if not integral may oscillate with the chaser holders or independently thereof. Preferably the chaser holders are rigidly secured to the trunnions or else integral therewith. At the rear ends of the trunnions are threaded bores to receive screws 35 having flat heads. The bores are provided with shoulders 36 (preferably annular) and in a preferred construction the under face of the flat head of a screw bears against the annular shoulder 36 at one side and the adjacent flat end of the trunnion bears against the other parallel flat face of the shoulder 36. Set screws 37 are located in threaded openings in the flat heads of the

screws and bear against the adjacent faces of the trunnions thereby insuring against accidental loosening of the screws and providing means for holding the parts securely in place, the resulting absolute parallelism of the adjacent faces of the trunnion and the screw head being particularly advantageous in die heads where all parts should have rigid permanent positions while in operation as far as possible and where strict parallelism of the planes of movement of the cutter-holders and parts moving therewith is highly essential.

The head body is hollow and the shank also has a longitudinal aperture of smaller diameter than the bore of the head body. A trip is located in these bores said trip being movable axially of the die head and comprising a head 38 with longitudinal flanges. An annular flange 39 at the rear end of the head fits closely in the bore of the head body and a cylindrical extension in the form of a rod 40 lies mainly in the bore of the shank. The rod 40 is flattened at one side as shown in Figure 5 and a threaded plug 41 in said bore engages the threaded interior of the same, said plug contacting with the rear end of the rod whereby the trip may be adjusted lengthwise in the bore of the head body to predetermine the length of threads on the work in an adjustable manner. A set screw 42 engages the rod 40 at its flat side for locking the same against accidental movement.

From the foregoing it will be understood that the head body can be rotatably adjusted relatively to the ring 16 and the shank for varying the diameter of the opening between the jaws in open and closed position respectively. The jaws can also be moved from open to closed position and back by rotation of the ring 17 which may be done by operating the handle 19 either manually or mechanically to close the head. This brings the chasers 31 into engagement with the work 43 whereupon a screw-thread is cut by the longitudinally adjustable tangential chasers 31 which are hardened bars that have had the thread contours milled in one side so as to permit end sharpening, that is, they are of the Landis type and this continues until the work strikes against the end of the trip as shown in Figure 4 whereupon the continued rotation of the head and the work relative to each other draws the head body and the rings 15, 16 and 17 forward rela-

tively to the shank and the pins 23. When this operation has proceeded so far as to withdraw the reduced ends of the pins from the recesses in the ring 17, the resistance of the work to the action of the chasers 31 together with the operation of resilient means not shown in the drawings throws the jaws out and brings the head into open position.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. In a die head, a drilled shank, a hollow head body movable axially relatively to the shank, chasers on the head body, an oscillatory ring for moving the chasers into and out of operative position, one or more pins fixed relatively to the shank arranged to engage said oscillatory ring for holding the chasers in operative position said pins being wholly withdrawn from said ring by said axial movement to release the chasers from the work and a trip carried by the head, said trip comprising a work contact head within the head body and a stem within the shank, means within the shank providing axial adjustment for the stem and a flange on the work contact head forming a sliding fit with the interior of the hollow head, so that axial stoppage of the work by the trip enables the chasers to move the head body relative to the shank, substantially as set forth.

2. In a die head, a head body, rings surrounding the body, an integral circumferential flange at the end of the body for holding the rings in place, a supporting shank for the body bearing against the rearmost ring, said shank movable axially relatively to said ring, a shoulder on the said body, a ring about and secured to the body behind said first named rings for confining one of them against said shoulder and trip means movable axially within said body, substantially as set forth.

In witness whereof, I have hereunto set my hand at Waynesboro, Pennsylvania, this 12th day of November, A. D. nineteen hundred and twenty-four.

SAMUEL F. NEWMAN.
